GEORGE P. BUTLER, OF LEBANON, NEW HAMPSHIRE.

BIT.

1,321,007.

Specification of Letters Patent.

Patented Nov. 4, 1919.

Application filed June 17, 1916. Serial No. 104,279.

To all whom it may concern:

Be it known that I, GEORGE P. BUTLER, a citizen of the United States, residing at Lebanon, in the county of Grafton and State of New Hampshire, have invented new and useful Improvements in Bits, of which the following is a specification.

This invention relates to improvements in machine bits. More particularly it relates to improvements in the points of augers or other boring tools for wood or the like. In order to perform successfully its function of centering the tools, the point of a bit must have adequate strength, which means a considerable diameter. In order to penetrate the wood the point is usually made more or less conical. As the cutting parts of the bit do not make a hole for the entrance of this conical point into the wood the propulsion of this conical point through the wood requires the use of pressure which develops friction that is damaging to the temper of the tool. In hand augers it is customary to erect a screw thread on the cone, which draws in the point as the bit is rotated; but machine bits rotate at such a speed that the use of a screw point is not feasible. In its place it has been customary to use smooth points, or diamond points; but whatever its shape a point has to be pushed into the wood by force as the operator feeds the bit into the work. To get the best results it is customary to rotate the bit at high speed, so that the cutters shall be able to do as much of their work as possible before the momentum is lost. So much friction results that the point becomes heated and soon loses its temper. Furthermore a bit which has to be forced by this means is not completely under the control of the operator. It is among the objects of the present invention to provide means so that the feeding of the bit shall remain constantly and delicately under the control of the operator; means by which the bit may operate successfully at a rotatory speed considerably below present practice, thus greatly reducing friction; means by which the efficiency of cutting is at the same time increased because at the lower speed thicker chips can be made, with a shorter total distance of actual cutting-edge-travel through

the wood in order to accomplish a given depth of cutting; and means by which the effort needed to drive the point through the wood is largely transferred to the machine, such part as remains to be executed by the operator being well within the control of a man.

Other results obtained by the invention, flowing from the attainment of these objects, are that the life of the bit is prolonged greatly; and that the output of a machine in a given time is multiplied by two or three, notwithstanding the reduced speed.

These objects are accomplished by shaping the point of the bit as a compound cam, the surface of which would be generated by an element whose movement is simultaneously spiral and helical with respect to the axis, starting with a needle-like solid, which constitutes the tip of the point, and which is of such small cross-section that it can be pushed into the wood with easy effort of the operator, or of feeding means provided in the machine. When in operation, no pressure is needed beyond that requisite to insert this needle tip, for the work of enlarging the hole it has made, so that the whole point can be housed therein, is done by the machine because of the spiral nature of the cam, assuming of course, that the operator keeps on pushing the point. The shape of the whole point thus constituted provides a safety device, preventing progress at more than a certain rate.

An embodiment of the invention is illustrated in the accompanying drawings in which:

Figure 1 is a side view of a machine bit; Fig. 2 is a side view of the same after being turned 90°;

Fig. 3 is a side view of the same with the spur nearest the eye cut away to disclose the base of the point.

Fig. 4 is an end view of the form shown in Fig. 2; and

Fig. 5 is a side view of a modification with part cut away as in Fig. 3.

Referring to the drawings, 10 indicates the shank, 11 the twist, 12 the peripheral cutting points, and 13 the radial cutting edges of an auger, which is the particular style of machine bit selected for illus-

tration. The point of the bit has a helical spiral surface. Its most advanced part has a tip 14 so small in diameter that it can be readily pressed into the stock upon which 5 the auger is to work.

From this narrow diameter the cross sectional size of the point increases along a spiral to the larger size indicated at the base 15, next to the radial cutting edge 13. 10 The spiral line 17 is seen in the end view, Fig. 4. From this line a surface 16 extends along the axis of the tool, the convolutions of this spiral surface being also convolutions of a helix whose course is defined 15 by the same line as seen in Figs. 1, 2 and 3. The said line is really the corner between the said surface and an abutment 18 which faces toward the tip of the point and has a width determined by the pitch of the 20 spiral. This width is obviously great enough and blunt enough to arrest the direct advance of the point into the work, except as the helical form of the abutment permits such progress upon rotation of the tool. This 25 is the safety feature above referred to, preventing too rapid thrusting of the tool into the work. The progress into the work may however be as much slower than this as is desired. In one preferred form the 30 surface 16 is parallel to the axis, in which case rotation produces no pull as of a screw thread drawing the point into the wood. Whatever part of the point has penetrated 35 merely revolves in the hole it has made until it is pushed farther in; and whenever it is pushed farther in, the hole is enlarged to receive it by the spiral component, which, because it is compounded with a helix, becomes of larger cross section by gentle 40 gradation and so slowly, by comparison with the speed of rotation of the tool, that it can and does easily expand the hole. The power for doing this is exerted in all directions in planes perpendicular to the axis 45 of the tool. Hence the force driving it has practically no component in the direction of said axis; and hence the force, and power, for this are supplied practically wholly from the rotatory power of the machine, 50 and not from the feeding means, whether hand or otherwise, which the machine has for driving the point into the work. The hole being thus enlarged by the cam-like spiral surfaces acting in planes perpendicular to the axis, the tool can itself be pushed along in the direction of the axis without effort so far as the point is concerned except what is required to introduce the tip 55 of the point farther into the work, which is little.

And even this little is reduced if the very tip of the point has an abrasive or a cutting edge and is a little eccentric so that it rotates or revolves through a small circle about

the axis, abrading the wood in front of it 65 as it does so. The convex angular edge 17 between the surfaces 16 and 18 is eccentric throughout its whole length in a certain sense because of its spiral form, *i. e.*, any particular point therein is farther from the 70 axis of revolution than is the point which is directly opposite it on the other side of the axis. Hence in the rotation of the tool an abrasive effect can be attained for enlarging the hole which the point is entering, as distinguished from the mere spreading which would occur if a cone were driven in, with accompanying danger of splitting. Fig. 5 shows a spiral helical surface conceived as being generated by an element 75 having a shape concave toward the axis, illustrated at 16', being of this shape so that the approach of this line to the outer edge of the abutment 18 is at an acute angle. This makes a scraping or abrasive edge, particularly if it has some bur, so that the wood into which the point of the bit is being advanced is more or less abraded.

As every physical point in the combined spiral and helical line marking the apex of 90 this angle between surfaces 18 and 16' is thus off-center, these points in the aggregate being on all sides of the axis, the point as a whole runs true, the eccentricity of any one part being balanced by the eccentricity 95 of others all around the axis. It will be noticed that the angle between the surfaces 16' and 18 is too blunt to act as a screw, because the surface 16' at any given point has a radius approximately equaling the 100 radius of the extreme outer edge of the surface 18' directly in front of it; and this fact, taken in conjunction with the rapid rotation of the tool, makes the edge act more as a scraper. The small chips from this 105 can come away through the concave face of the surface 16'. Moreover, as the bit rotates its point is not in contact with the wood in which it is embedded except on the spiral, helical line which forms the outer limit of 110 the abutment 18. Hence the friction and the generated heat are not as great as in the case of smooth conical point, whose entire surface is pressed and rubbing close against the wood.

Variations may be made from the precise forms illustrated without departing from the scope of the invention. It is intended to cover by suitable expression in the appended claims whatever features of patentable 115 novelty exist in the invention disclosed.

I claim as my invention:

1. A bit for high rotative speed wood-boring having a point with needle tip and with lateral surface approximately parallel to the axis and extending in a spiral and helical course backward from the said tip to the base of the point.

2. A bit for high rotative speed wood-boring having a point with needle tip and with surface back of the tip composed of two elements, each spiral and helical, one of 5 which is an abutment facing forward, and the other of which is behind the crest of

the abutment and approximately equals it in radius; with an abrading edge between said elements.

Signed by me at Lebanon, New Hampshire, this tenth day of June, 1916.

GEORGE P. BUTLER.
